(57) **CLAIM**

An ornamental design for a folded check wallet, as shown and described.

DESCRIPTION

FIG. 1 is an isometric view of a folded check wallet from the top front viewpoint showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top elevational view thereof;

FIG. 7 is a bottom elevational view thereof;

FIG. 8 is an isometric view from the top front of the new design when folded;

FIG. 9 is a left side elevational view thereof;

FIG. 10 is a right side elevational view thereof;

FIG. 11 a rear elevational view thereof;

FIG. 12 is a front elevational view thereof; and,

FIG. 13 is a top elevational view thereof.
